UNITED STATES PATENT OFFICE.

JOSEPH WEIL, OF NEW YORK, N. Y.

NECKWEAR-HOLDER.

SPECIFICATION forming part of Letters Patent No. 775,955, dated November 29, 1904.

Application filed December 21, 1903. Serial No. 185,933. (No model.)

To all whom it may concern:

Be it known that I, JOSEPH WEIL, a citizen of the United States, residing at the city of New York, borough of Manhattan, county 5 and State of New York, have invented certain new and useful Improvements in Neckwear-Holders, of which the following is a specification.

The object of my invention is to provide a 10 new and improved neckwear-holder which is simple in construction, can be applied on any collar-button, and can be applied on and removed from the collar-button easily and rapidly.

15 In the accompanying drawings, in which like letters of reference indicate like parts in both the figures, Figure 1 is a perspective view of my improved neckwear-holder. Fig. 2 is a side view of the same, showing how it is 20 applied on a collar-button.

The neckwear - holder is composed of a spring-clamp of suitable construction adapted to receive the head of a collar-button and to be held by spring-pressure on the shank of 25 the collar-button. A ring or loop is provided on the spring-clamp in front of the space for receiving the collar-button head, which ring or loop serves for receiving and holding an article of neckwear.

30 As illustrated, the spring-clamp is made of spring-wire and is provided in its rear part with a separable spring-eye B, having the two spring side pieces C, the upper ends of which are carried downward in front of the 35 spring-eye to form a tongue E. These two spring side pieces can give laterally when pressed against the front of the button-head D, so as to permit the said head to pass through the spring-eye and so that the head will be in 40 front of the spring-eye—that is, between the

spring-eye and the tongue E—and the shank of the collar-button will be within the spring-eye. The wire parts forming the sides U of the front part of the clamp are then brought together side by side and are carried upward 45 in front of the spring-clamp and then bent over at their upper ends toward the top of the tongue E, so as to form an elongated ring or loop F a short distance in front of the spring-clamp and in the same vertical plane 50 as the spring-eye and the tongue E—that is to say, in a vertical medial plane that passes through the tongue E, the center of the spring-eye, and through this ring or loop F. The article of neckwear is passed through the loop 55 F and is then folded or shaped to present the desired appearance, and the fold may be then secured in place by a pin or may be otherwise confined in place, as may be desired.

Having described my invention, what I 60 claim as new, and desire to secure by Letters Patent, is—

A neckwear-holder, composed of a clamp having a separable spring-eye, and a loop through which part of an article of neckwear 65 can be passed, the said loop being in front of the spring-eye in a medial plane which is passed through the spring-eye between its separable side pieces, all made of a single and continuous piece of spring-wire, substantially 70 as set forth.

In testimony whereof I have signed my name to this specification, in the presence of two subscribing witnesses, this 19th day of December, 1903.

JOSEPH WEIL.
